RECTIFYING TUBE

Johannes Gisbertus Wilhelm Mulder and Daniel Marie Duinker, Eindhoven, Netherlands, assignors to N. V. Philips' Gloeilampenfabrieken, Eindhoven, Netherlands

Application October 3, 1935, Serial No. 43,429
In the Netherlands October 11, 1934

3 Claims. (Cl. 250—27.5)

Our invention relates to rectifying tubes and more particularly to ionic rectifying tubes having a plurality of anodes and a common incandescent cathode.

5 The term "ionic rectifying tube" as used herein and in the claims is to be understood to mean a tube whose filling consists of one or more gases or vapors, or a mixture of gases and vapors and has a pressure from several microns to several 10 centimeters of mercury.

Rectifying tubes according to the invention are particularly suitable for use in battery-charging circuits, and we shall describe our invention in this connection; however their use is not limited thereto.

15 According to the invention the anodes are located near to, and preferably symmetrically around a central cathode and some of the anodes are provided with means which increases their 20 negative blocking potential with respect to other anodes.

The above symmetrical spacing of the anodes makes it possible to shape the tube as a simple solid of revolution. Furthermore all of the 25 terminals can be conveniently grouped on one or the two ends of the tube. In either case the terminal connections can be made in a simpler manner to standard bases or the like.

The anodes and the cathode can be in such 30 close spacial relation, as not to occupy more space than that occupied by the electrodes of an ordinary full-wave rectifying tube, and in addition a minimum internal voltage drop and a maximum efficiency can be obtained.

35 To increase the blocking potential of some of the anodes with respect to others, they may be provided with shielding means for example by surrounding same with an electrically-conductive sleeve provided with an aperture which has a 40 smaller area than the front surface of the anode; the discharge towards the anode being limited to pass through said aperture.

For the same purpose, especially when high 45 alternating voltage differences occur between the anodes, electrostatic screens may be used to prevent the passage of an arc discharge between the anodes.

The rectifier tube according to the invention 50 may be advantageously used in circuit arrangements in which each anode of the tube together with its resistance, load and winding of the supply transformer—which winding is preferably provided with taps and a switch for selecting the desired tap—forms an independent half-wave 55 rectifying circuit; the only common portion of

the individual circuits being that portion which is associated with the incandescent cathode. Such an arrangement provides for a simple electrical system, whereby each circuit can be simply laid out in accordance with its particular current and voltage requirements. Furthermore, the danger of back discharges or mutual disturbances is reduced to a minimum. To prevent any magnetizing effect of the rectified current on the transformer it is preferable that the phase of 10 the alternating voltage of the individual anode circuits be such, that the direction of the rectified current as it passes a plurality of transformer windings be reversed.

Thereby the direct current components passing 15 through the windings as a result of half-wave rectification neutralize each other, when the various circuits of the rectifier are simultaneously loaded and for a given power a small transformer can be used.

In order that the invention may be more clearly 20 understood and readily carried into effect, it will be more fully explained in connection with the accompanying drawing, in which:

Figure 1 is a partly sectionized view of a rectifier tube according to the invention. 25

Figure 2 is a partly sectionized view of another tube according to the invention.

Fig. 3 is a circuit diagram employing the rectifier tube shown in Fig. 1. 30

The rectifier tube shown in Figure 1 has a vitreous envelope forming presses 58 and 62 and containing four anodes, 3, 4, 5, and 6 arranged symmetrically around and at a small distance from a common incandescent cathode 2. 35

The rectifier tube is provided on its end with caps 20 and 17 of insulating material carrying screw terminals 18 and 19 and plug pins 63, 64, 65, and 66 respectively.

The anode 5 is formed of a cylindrically-shaped block 57 of carbonaceous material, for instance of graphite, and is supported from pinch 58 by a supporting rod 60 of conductive material surrounded by a tube 61 of insulating material; the rod 60 being electrically connected by a lead 59 to the terminal 18. The anodes 3 and 4, which are of similar construction to anode 5 and are supported in a similar manner from press 62, are electrically connected by leads 13 and 14 to the pins 63 and 64 respectively. 40

The incandescent cathode 2 is supported from the press 62 by supporting rods 65 and 66 of conductive material which rods are electrically connected by leads 15 and 16 to pins 67 and 68 respectively. 45

Supported from the press 62 is a wire 10 provided with a temporary external lead 12 and carrying a piece of getter material 11, which material is volatilized during the evacuation of the tube by passing a discharge between wire 10 and the cathode 2.

The anode 6, which is destined to be operated on a higher voltage than are the anodes 3, 4, and 5, consists of a small cylindrical block 69, of carbonaceous material, for instance carbon, supported from press 58 and electrically connected to terminal 19 in a manner similar to that explained in connection with anode 5.

Suitably supported from a projecting portion 9 of the press 58 is a cap-shaped screen 7 of conductive material provided on its closed end with an aperture 8 centered with and having a smaller area than the front face of the anode 6. The projecting portion 9 extends downwards to surround a large portion of the rear end of the anode 6.

The projecting portion 9 and screen 7 thus serve to screen the anode 6 whereby the discharge from cathode 2 must pass through the aperture 8 to the front face of the anode 6, and the negative blocking voltage of this anode is considerably increased over that of anodes 3, 4, and 5. The screen 7 is of small size and the entire assembly of anode 6 together with its screening means occupies no more space than do the lower voltage anodes.

In the tube shown in Fig. 1 the terminals for the incandescent cathode 2 and the anodes 3 and 4 are located at the lower end of the tube, whereas the terminals for the anodes 5 and 6 are located at the upper end. This arrangement has the advantage that the base 17 may be a standard four-pin base and thus can be inserted into a standard socket. It is preferable to connect the anode or anodes used for the higher negative blocking potential to the terminals 18 or 19, as this provides a long insulating path between the terminals of the high-tension anodes and the remaining terminals. It may be advisable, particularly when the anode voltages are not too high, to locate all the anode terminals on the same end of the tube as are the terminals for the incandescent cathode, in which case a standard six-prong base, and thus a standard socket, can be used.

The tube may have a gaseous or vapor filling, for example argon at about 4 millimeters pressure, or argon at about 0.7 millimeter, together with a supply of mercury.

The tube shown in Figure 2 is substantially the same as that shown in Figure 1, only the location of the anode 81 is exactly the same as that of the remaining anodes and a metal screen 90 prevents the occurrence of arcing between the anodes 57 and 81. Thus the blocking potential of these anodes with respect to each other is materially increased. A cylindrical portion 91 of the metal screen 90 surrounds the cathode 2 and is connected at 92 to one of the supply conductors of the cathode 2. This measure results in a substantial increase of the blocking voltage sustained by the discharge paths from the cathode to any of the anodes of the tube.

The tube shown in Figs. 1 and 2 is adapted for use in various circuit arrangements, one of such circuit arrangements with a tube according to Fig. 1, which is for charging four batteries 81, 82, 83, and 84 of different current capacities, being shown in Fig. 3.

The circuit arrangement shown in Fig. 3 consists of a transformer C having a primary winding 22 connected through a two-pole switch 21 to a suitable alternating current supply, and four secondary windings 70, 71, 72, and 73, each provided at one end with a plurality of taps. Arms 23, 24, 25, and 26 serve to select the desired tap of windings 70, 71, 72, and 73 respectively.

The rectifier tube B, which is schematically shown, is of the same construction as the tube shown in Fig. 1, and has its electrodes indicated by the same reference numerals as in Fig. 1.

The incandescent cathode 2 has its ends connected to a heating winding 74, provided either on the transformer A or on a separate heating transformer, and having a center tap 80 connected through conductor 86 to the positive terminals 43, 44, 45, and 46 of batteries 81, 82, 83, and 84.

The winding 70 has one end connected through an ammeter 33 to the negative terminal 56 of battery 84, and is connected through arm 23 and a resistance 75 to the anode 3. By changing the position of arm 23 connection may be made to various taps on winding 70 and the alternating voltage applied to anode 3 can be changed.

Similarly to winding 70, one end of winding 72 is connected through ammeter 35 to the negative pole 54 of battery 82 and through arm 25 and resistance 77 to anode 5.

The winding 73 has one end connected through a resistance 78 to anode 6 and has its other end connected through arm 26 and ammeter 36 to the negative terminal 53 of battery 81. In a similar manner one end of winding 71 is connected through resistance 76 to anode 4 and its other end is connected through arm 24 and ammeter 34 to the negative terminal 55 of battery 83.

It should be noted that windings 70, 71, 72, and 73 are so arranged on the transformer A that the rectified current components in windings 70 and 72 are opposite in direction to those in windings 71 and 73. This prevents any magnetization effect on the transformer by the direct current components and thus a smaller transformer can be used for the same power.

Thus it is seen that there is an individual rectifying circuit for each of the anodes, which circuits have in common only that portion between the cathode 2 and the positive terminals of the batteries.

To charge batteries of widely varying current capacities, it is advisable to compute the individual rectifying circuits—either for the lower or at the higher voltage values—for different current values which current values are preferably made evenly progressive. This permits the batteries to be charged in distinct series according to their current capacities, and also allows—by selecting the proper tap on the transformer winding—the matching of individual charging circuits with the number of cells used in the various series.

The individual rectifying circuits can be calculated for any desired values, however in the present instance the rectifying circuits corresponding to anodes 3, 4, 5, and 6 are calculated to charge batteries having a minimum of 12, 12, 12, and 60 lead cells respectively, at charging currents of 1, 2, 3 and 0.25 amperes respectively.

While we have described our invention in connection with specific examples and specific applications, we do not wish to be limited thereto, but desire the appended claims to be construed as broadly as permissible in view of the prior art.

What we claim is:

1. An ionic rectifying tube comprising an envelope, an incandescent cathode, a plurality of anodes disposed in the same discharge space with said cathode, said anodes being symmetrically mounted around said cathode and at equal distances therefrom, and means to increase the negative blocking voltage of one of said anodes to a value greater than that of the remaining anodes.
- 10 2. An ionic rectifying tube comprising an envelope, an incandescent cathode, a plurality of anodes disposed in the same discharge space with said cathode and close thereto, said anodes being symmetrically mounted around said cathode and at equal distances therefrom, and a cup-shaped member of electrically conductive material surrounding one of said anodes to increase the negative blocking voltage thereof, said member being

provided with an aperture centered with the front face of said anode and having an area less than that of the front face of the anode.

3. An ionic rectifying tube comprising an envelope, an incandescent cathode, a plurality of anodes disposed in the vicinity of said cathode and in the same discharge space therewith, means to increase the negative blocking voltage of one of said anodes, a four-pin base secured to one end of said tube, leads connecting two of said anodes to two of the pins, and leads connecting said cathode to the other two pins, the remaining anodes being connected through the envelope at the other end of the tube.
